INVENTOR

Albert Eppler
By his Atty. Walter B. Thorne

UNITED STATES PATENT OFFICE.

ALBERT EPPLER, OF PROVIDENCE, RHODE ISLAND.

DESIGN FOR A LACE-PIN.

SPECIFICATION forming part of Design No. 20,587, dated March 17, 1891.

Application filed October 1, 1890. Serial No. 366,763. Term of patent 3½ years.

To all whom it may concern:—

Be it known that I, ALBERT EPPLER, of Providence, in the State of Rhode Island, have invented and produced a new and original Design for Lace-Pins, of which the following is a specification, reference being had to the accompanying drawing, forming a part of the same, which represents a front view of a pin embodying my design.

5 The leading features of my design consist in a conventionalized representation of the

letters "M" and "Y" and the figure of a deer. The letters form a base or background upon or across which is placed the deer.

Having thus described my design, I claim— 15

The design for a lace pin, substantially as herein shown and described.

ALBERT EPPLER.
